[57] **CLAIM**

The ornamental design for a rod holding adapter for a cantilever bracket, as shown and described.

DESCRIPTION

FIG. 1 is a perspective view of the rod holding adapter for a cantilever bracket, showing my new design, wherein the broken lines are for environmental purposes only and form no part of the claimed design;

FIG. 2 is a side view thereof, the opposite side being a mirror image thereof;

FIG. 3 is a front view thereof, the back view being a mirror image thereof;

FIG. 4 is a top view thereof;

FIG. 5 is a bottom view thereof; and,

FIG. 6 is a bottom, front perspective view thereof.
